CLAIM

The ornamental design for a foldable toilet footrest, as shown and described.

DESCRIPTION

FIG. 1 is a perspective view of the foldable toilet footrest; FIG. 2 is a top plan view of the foldable toilet footrest; FIG. 3 is a front elevation view of the foldable toilet footrest; FIG. 4 is a back elevation view of the foldable toilet footrest; FIG. 5 is a right side elevation view of the foldable toilet footrest; FIG. 6 is a bottom plan view of the foldable toilet footrest; and, FIG. 7 is a perspective view of the foldable toilet footrest collapsed. The broken lines in the drawings depict portions of the foldable toilet footrest that form no part of the claimed design.
